now Design Patent No. 200,903, dated Apr. 20, 1965.
Divided and this application Dec. 4, 1964, Ser. No.
83,268

Claims priority, application Japan Mar. 19, 1963

Term of patent 14 years

(Cl. D18—2)

FIG. 1

FIG. 2

FIG. 3

FIG. 4

FIG. 1 is a plan view of a planar side of a mosaic tile embodying my new design;

FIG. 2 is an end elevational view of the right edge of the tile in the FIG. 1 orientation;

FIG. 3 is a plan view of the side of the tile opposite that shown in FIG. 1; and

FIG. 4 is an end elevational view of the right edge of the tile in the FIG. 3 orientation.

This is a division of application Serial No. D-76,436, filed September 3, 1963, now Patent No. D-200,903.

I claim:

The ornamental design for a mosaic tile, as shown.
